UNITED STATES PATENT OFFICE

2,357,454

OIL BURNER

William C. Brown, Detroit, Mich.

Application March 20, 1941, Serial No. 384,291

1 Claim. (Cl. 158—91)

This invention relates to oil burners and particularly to a small capacity burner of the type utilized in connection with ranges, hot water heaters, and steam and air furnaces.

It is a general object of the invention to provide a midget oil burner particularly adapted for use in place of gas burners on ranges and on small size heating units, such as those utilized to heat small store rooms, individual offices, or in connection with hot water heaters or small steam boilers such as those used for supplying steam to clothes pressing machines and the like. Accordingly, in the present invention, there is provided a small, compact, inexpensive oil burner assembly having a unique type of oil burning receptacle.

Another object of the invention is to provide an oil burner assembly comprising a burner unit, motor driven fan, air and oil conduits, oil flow control mechanism, and an oil burning receptacle all fixedly connected together for installation as a compact, self-contained unit.

Another object of the invention is to provide an improved and simplified burner unit, in which an efficient combustion of the fuel oil is achieved.

Other objects and advantages of the invention will become apparent from the following specification and claim and the accompanying drawing, wherein:

Figure 1 is a perspective view of an oil burner embodying features of my invention;

Fig. 2 is a perspective view of the oil burning receptacle of the burner illustrated in Fig. 1;

Fig. 3 is a broken, reduced plan view of the oil burner unit illustrated in Fig. 1; and

Fig. 4 is an enlarged, sectional view of the burner end of the structure illustrated in Fig. 1.

The oil burner unit 10, illustrated in Figs. 1 to 4, comprises a motor 11 and fan 12 connected together as a unit and supported by the fan discharge outlet 13 which extends within a flanged collar 14. The flange of the collar 14 is bolted directly to a mating flange on a burner air conduit 15 by bolts 16. The discharge outlet 12 of the fan is secured within the collar 14 by any suitable means such as set screws 17. The conduit 15 is circular at the flange, but reduces in height and increases in width as it approaches the burner proper and is provided with a flat bottom surface by which it may be supported.

Float valve mechanism 20 is supported upon a bracket 21 which is bolted at 22 to the underside of the conduit 15, as illustrated in Fig. 3. If desired, a steam pressure responsive control valve

mechanism 25 of any desired type may be positioned in the oil feed line for the purpose of cutting off the flow of fuel oil when the boiler pressure reaches a predetermined amount. It is to be understood, however, that if the furnace is to be used for general heating purposes, a thermostatically controlled valve, well known in the art, may be substituted for the pressure responsive valve mechanism 25.

10 A burner housing 27 is formed integrally with the conduit 15 and comprises a substantially cylindrical, upwardly opening chamber in communication with the conduit 15. Positioned within and spaced from the walls of the burner housing 27 is a fire pot 28 which is preferably cast integrally with the burner housing and conduit. The connection between the fire pot and the burner housing and conduit is through an integrally cast rib 29 which is provided with a bore 31 communicating with the interior of the fire pot 28 and adapted to be connected to the oil intake pipe 32, the opposite end of which is connected to the float control mechanism 20 through the valve 25. An auxiliary bore 33 is provided in the rib 29 for use in connecting the oil line in cases where there is insufficient room beneath the bottom of the burner to receive the oil supply pipe.

An oil receiving and burning receptacle 35 forms 30 a bottom of the fire pot 28, having a central opening 36 connected to a pipe 37 which is screwed into the casting in communication with the bore 31. The base of the cup has annular corrugations 38 which are interrupted by radially disposed grooves 39 radiating from the opening 36. Downwardly projecting lugs 40 support the peripheral edge of the cup while a pair of inwardly disposed lugs 41 may be provided to be engaged by a spanner wrench for screwing the cup on the pipe 37.

At the end of the air conduit 15 within the burner housing 27, a baffle 42 divides the air passing through the conduit which flows around both sides of the fire pot 28 and upwardly thereabout. 45 An air directing ring 43 rests upon the top of the burner housing 27 having an inwardly directed flange 44. The underside of the flange is curved at 45 for directing the air moving upwardly between the housing 27 and fire pot 28 toward the cup 35. The end of the ring opposite to the conduit 15 has a flanged portion 46 extended inwardly to prevent the air from passing upwardly rather than downwardly into the cup 35. The ring 43 assures a uniform flow of air toward the base of the cup 35 from all points of its periph-

ery. The oil passes through the conduit 32, the bore 31, the pipe 37, and through the radial slots 39 into the troughs 47 provided between the corrugations. The height of the oil within the slots 39 and troughs 47 is regulated by adjusting the float in the float control mechanism 20.

The burner operates as a low and high flame burner, the oil being normally delivered in a very small quantity, enough to keep a flame burning within the cup 35. When heat is required, the control mechanism operates the valve 25 to supply a greater flow of oil to the cup 35 which increases the size of the flame and the rate of burning of the oil. At the same time, motor 11 operates the blower 12 to force air through the conduit 15 which is divided by the baffle 42 to flow around and upwardly of the fire pot 28. The air strikes the arcuate surface of the ring 43 and is deflected into the receptacle or cup 35 to provide the increase in air for combustion.

After the temperature of the water, air or other substance being heated has reached a predetermined degree, the control mechanism operates the valve 25 to reduce the flow of oil to the cup 35. The operation of the motor 11 is interrupted and the burner thereafter functions on a low or pilot flame. It is to be understood that when the burner is employed on a range that a manual control valve is provided for turning the burner on and off as desired.

The oil receiving and burning cup 35 is herein

illustrated as being a casting but it is to be understood that the cup could be stamped or otherwise formed from sheet metal. By having the base of the cup corrugated, the oil burns in rings interrupted by the radial flames produced by the oil burning in the slots 39. The low flame in the cup functions as a pilot light without the application of air through the conduit 15. The high flame is produced by an increased delivery of oil and the positive flow of air into the oil burning cup to assure complete combustion. The air is directed into the cup by the ring 43, after the baffle 42 divides the air to have it flow equally about the pot.

What I claim is:

An oil burning unit comprising an upwardly open casing, a lateral air supply conduit communicating with said casing adjacent the bottom thereof, a fire pot within said casing having walls spaced from the walls of said casing whereby air from the conduit will pass upwardly between said walls, a cup having a corrugated bottom disposed within and forming the base of the fire pot, and conducting means for oil communicating with the center of said cup, said corrugations being interrupted by co-planar radial grooves each of which extends to the center of the cup for delivering the oil directly to the troughs formed between the corrugations and for draining the oil in said troughs into said conducting means.

WILLIAM C. BROWN.
